UNITED STATES PATENT OFFICE.

MAURICE D. PENDERGAST, OF HUTCHINSON, AND JAMES M. WHIDDEN, OF ST. PAUL, MINNESOTA, ASSIGNEES, BY DIRECT AND MESNE ASSIGNMENTS, TO JUDITH M. PENDERGAST, OF HUTCHINSON, MINNESOTA.

FENCE-MAKING MACHINE.

SPECIFICATION forming part of Letters Patent No. 628,253, dated July 4, 1899.

Application filed July 5, 1898. Serial No. 685,106. (No model.)

To all whom it may concern:

Be it known that we, MAURICE D. PENDERGAST, residing at Hutchinson, in the county of McLeod, and JAMES M. WHIDDEN, residing at St. Paul, in the county of Ramsey, State of Minnesota, citizens of the United States, have invented certain new and useful Improvements in Fence-Making Machines; and we do hereby declare the following to be a full, clear, and exact description of the invention, such as will enable others skilled in the art to which it appertains to make and use the same.

This invention has for its object to provide an efficient machine for producing a wire fence of the kind disclosed in the United States patent issued to Maurice D. Pendergast, of date January 4, 1898, under No. 596,538.

The machine herein disclosed is a power-driven automatic machine. Some of the features of the invention, however, would be capable of use in a hand-machine.

The invention is illustrated in the accompanying drawings and will be hereinafter fully described, and defined in the claims.

In the said drawings like notations refer to like parts throughout the several views.

Figure 1 is a diagram view illustrating the disposition of the wires with respect to each other as they would appear before being twisted together to form the fence. Fig. 2 is a diagram view intended to illustrate the action of the fence and the wires as they appear related to each other when the fence is being made. Fig. 3 is a plan view of the machine with some parts broken away and others removed, the loop-wires only being shown in position thereon. Fig. 4 is a side elevation of the machine. Fig. 5 is a vertical cross-section through a part of the machine approximately on the line $x^5 x^5$ of Fig. 3, with some parts removed and others broken away. Fig. 6 is a detail in perspective, showing shipper-lever and trip-rod forming part of the reversing-drive for the traveling carriers which dispose the loop-wires. Fig. 7 is a similar view showing the counterweighted lever which co-operates with the shipper-fork shown in Fig. 6. Fig. 8 is a view, partly in

side elevation and partly in section, with some portions broken away and others removed, illustrating on a larger scale the mechanism at the central part of the machine as it appears in Fig. 4. Fig. 9 is a detail showing some of the same parts shown in Fig. 8, but with the master-wheel removed to expose the mate wheel, which co-operates therewith, and some of the parts broken away. Fig. 10 is a detail showing one of the twister-holders in side elevation detached. Fig. 11 is a view of the same in vertical section on the line $x^{11} x^{11}$ of Fig. 8. Fig. 12 is a detail showing the driving-arm, which reverses the motion of the mate wheel, in side elevation, detached. Fig. 13 is a detail in side elevation, showing an arm, which is keyed to the rock-shaft shown in Figs. 8 and 9, detached. Fig. 14 is a detail of the loose rocker-arm detached, which is mounted on the rock-shaft, as shown in Figs. 8 and 9, for co-operation with the members shown in Figs. 12 and 13. Fig. 15 is a view, partly in side elevation and partly in section, with some portions broken away and others removed, showing some of the same mechanism as in Fig. 8, together with some additional parts, but with the twister-holders as they would appear at the limit of their releasing action in full lines and in an intermediate position in dotted lines. Fig. 16 is a vertical section on the line $x^{16} x^{16}$ of Fig. 8, with some parts in elevation and some parts broken away. Fig. 17 is a vertical section on the line $x^{17} x^{17}$ of Fig. 15. These two views, Figs. 16 and 17, show the same parts, but in different positions. Fig. 18 is a detail of the trip for the master-wheel detached. Figs. 19 to 24, inclusive, are diagram views illustrating the reverse-motion and differential drives for the twisters. Fig. 25 is a detail in perspective, showing one of the holders of what may be called the "side" or "marginal" wire twisters as distinguished from the others, which may be called the "loop-wire" twisters or "stay-twisters." Fig. 26 is a detail in section, illustrating one of the twisters carried by the holders, one of which is shown in Fig. 25. Fig. 27 is a detail in section, approximately on the line $x^{27} x^{27}$ of

Fig. 3, illustrating the feed-clamp for the fence. Fig. 28 is a vertical section crosswise of the machine, approximately on the line $x^{29} x^{29}$ of Fig. 3, with some parts removed and others broken away, the twisters being sectioned through their mouths in twisting position. Fig. 29 is a detail in longitudinal section lengthwise of the machine, approximately on the irregular line $x^{29} x^{29}$ of Fig. 28. Fig. 30 is a view, partly in diagram, partly in plan, and partly in horizontal section, through the twisters for illustrating the drawing action permitted thereby on the stays when the twist is being made. Fig. 31 is a detail in side elevation, showing one of the expandable twisters detached. Fig. 32 is a vertical section on the line $x^{32} x^{32}$ of Fig. 31. Fig. 33 is a section through a pair of the expandable twisters on the line $x^{33} x^{33}$ of Fig. 31. Fig. 34 is a vertical cross-section through the machine, approximately on the line $x^{34} x^{34}$ of Fig. 3. Fig. 35 is a view, partly in rearelevation and partly in vertical section, showing the winding-up reel. Fig. 36 is a section on the line $x^{36} x^{36}$ of Fig. 35. Fig. 37 is an inside elevation of one of the reel-heads detached. Fig. 38 is a detail in vertical section on the line $x^{38} x^{38}$ of Fig. 34 for showing the pawl-and-ratchet drive applied to the driven member of the coöperating pair of delivery-rolls at the foot of the machine, and Figs. 39 and 40 are diagram views illustrating some of the driving connections.

The construction and action of the machine can be best understood by first calling attention to the product and the primary disposition of the wires for producing that product, as illustrated in Figs. 1 and 2. Using the same terms as were employed in the above-noted Pendergast patent, No. 596,538, the wires 1 and 2, which take such disposition as to form the vertical stays of the fence when the wires are properly twisted together, were in said patent called the "loop-wires." The intermediate wires 3, embraced by the loop-wires and securely held thereby when the loop-wires are twisted into stays, were in said patent called the "filling wires or cables," as they are of cable form, and the marginal wires 4, to which the horizontal sections of the loop-wires 1 and 2 are locked when the said parts are twisted together, as shown in the modification illustrated in Figs. 4 to 6, inclusive, of said prior patent, were therein called the "lock-wires."

By inspecting the diagram Fig. 1 it will be seen that the two loop-wires 1 and 2 alternately change places at the top and bottom of the fence in the horizontal sections of the loops. Otherwise stated, they extend crosswise of the filling-wires alternately in opposite directions and embrace the said filling-wires 3 between the vertical sections of the loops. The lock-wires 4 extend parallel and near to the horizontal sections of the loop-wires. By this disposition the vertical sections of the loop-wires are brought into posi-

tion to permit the same to be twisted together between the filling-wires and the horizontal sections of the loop-wires to be twisted to the lock-wires 4.

It should further be noted that the twists applied to the vertical sections of the loop-wires to form the vertical stays of the fence are in opposite directions for adjacent twists. Otherwise stated, the twists alternate. Moreover, it may be further noted that the spaces between the filling-wires differ from each other in the vertical direction, or, otherwise stated, the lower strands of the fence are closer together than the upper strands. It is therefore necessary to give a greater number of twists to the loop-wires at the wider spaces. Hence differential drives are required for the twisters, as will later appear.

It must also be obvious that when the twists are applied to the loop-wires for forming the vertical stays of the fence a draw will be produced thereon, resulting in shortening the loops to the height shown in the finished fence. In other words, the stay is shorter than the vertical sections of the untwisted loops. In this machine sufficient twisters are provided for making all of the twists simultaneously. Hence provision must be made for the said shortening or drawing action on the vertical sections of the loop when the twists are being made. It is also desirable that the draw should be distributed as evenly as possible among the different spaces or, more accurately stated, throughout the entire length of the stays. To accomplish these results, the twister most centrally located is taken as the base for the draw and is non-expandable. The other twisters which operate on the vertical sections of the loop-wires to form the vertical stays of the fence are so constructed as to be expandable and contractible.

In the diagram view Fig. 2 the notation for distinguishing the individual wires above noted is preserved for the loop-wires 1 and 2 and the lock-wires 4 only up to the time that they are twisted together and their individuality lost as the fence is formed. The vertical stays resulting therefrom are marked with the numeral 5 in the fence, and the marginal or top and bottom cables resulting therefrom are marked with the numeral 6. The filling-cables 3 never change their form and are marked with the same numeral 3 throughout.

The machine will now be described. The main frame of the machine and such of the fixed parts projecting therefrom as it may be necessary to note will be marked with the reference-letter *a* and the powers thereof. Bearings and other such obvious parts will not be noted by reference-letters unless desirable in order to locate and distinguish some of the moving parts.

The wire-supplying and fence-feeding devices.—The upper member 1 of the two loop-wires is shown as being unwound from a spool 1^a, suitably supported from some over-

lead structure by a hanger 1^b or otherwise. The lower member 2 of the pair of loop-wires is shown as being unwound from a spool 2^a, journaled in a support 2^b, fixed to the floor 5 or other part of the building below the working deck of the machine. (See Fig. 4.) The filling-cables 3 and the lock-wires 4 are also unwound from suitable spools (marked with the common numeral 7) shown in Fig. 4 as 10 turning on spindles 8, rising from a fixed support 9, suitably spaced apart from the head of the machine. The filling-wires 3 and the lock-wires 4 pass first between sets of sheaves b, arranged three high on suitable 15 supporting-brackets a' at the head end of the machine. The apex member of these three sheaves b would in practice be mounted for vertical adjustment on its supporting-bracket a' for varying the tension between the three 20 sheaves b. These sets of three sheaves b serve to straighten the wires and subject the same to suitable tension. Hence they may be called the "tension" and "straightening" devices. From the sets of sheaves b the filling-wires 3 and the lock-wires 4 become subject to a pair of drums b' b², passing under the drum b' and over the top of the larger drum b². These drums serve to equalize the 25 pull from the spools when the fence is fed forward and prevents slack in said wires on the fence side of said drums. The said pair of drums b' b² may, therefore, be conveniently called the "equalizers." They afford such a 30 large amount of frictional surface for action 35 on said filling-wires 3 and lock-wires 4 that the said wires cannot slip, or, otherwise stated, will only unwind from their supplying-spools 7 with a positive feed equal to the forward step of feed movement given to the finished fence.

From the equalizing-drums b' b² the filling-wires 3 and the lock-wires 4 extend directly to the delivery-rollers b³ b⁴, located at the foot of the machine. The said rollers b³ 45 b⁴ are rubber-faced and located one directly over the other. The wires 3 and 4 pass over the top of the upper roller b³ and then back between the two rollers and out under the lower roller b⁴ to the winding-up reel p' p', &c., the details of which will be later described. It is sufficient to note at this time that by the 50 above disposition of the wires 3 and 4 the fence is held taut in whatever position it may be moved under its feed devices. This fact 55 also permits that portion of the fence which is wound upon the reel to be severed from the other part remaining held by the machine, as will later more fully appear. The said two delivery-rollers b³ b⁴ are geared together by 60 spur-wheels b⁵, as best shown in Figs. 4 and 34. They therefore turn in opposite directions. On the hub of the gear-wheel b⁵, fixed to the shaft of the upper delivery-roller b³, is a ratchet-wheel b⁶, with which engages a retaining-pawl b⁷, pivoted to a part of the fixed framework, as best shown in Fig. 3. The 65 shaft of the upper member of said delivery-rollers b⁸ extends outward beyond the machine-frame at both ends and is provided with ratchet-wheels b⁸, fixed thereto, and sprocket-wheels b⁹, loose thereon. The sprocket-wheels b⁹ have on their profile faces, adjacent to the ratchets b⁸, pawls b¹⁰, which engage with the ratchet-wheels b⁸ for turning the delivery-rollers forward under the feeding action on 70 the fence. This construction will of course permit the sprockets b⁹ to turn backward on their supporting-shaft, while the delivery-rollers are held stationary under the coöperation of the retaining ratchet-and-pawl devices b⁶ b⁷. On the loose sprockets b⁹ and coöperating idle sprockets b¹⁰, located on the framework a considerable distance farther inward toward the center of the machine, as best shown in Fig. 3, are mounted a pair of 75 chains b¹¹. To the said chains b¹¹ are fixed arms b¹², projecting from a plate b¹³, extending crosswise of the machine and over which the fence passes. On account of its function, to be presently noted, the plate b¹³ may be called 80 the "base-plate" of the fence-clamp. The said base-plate b¹³ is provided at its opposite ends with upwardly-projecting short standards b¹⁴, (best shown in Fig. 27,) in which standards is mounted a rock-shaft b¹⁵. To the rock-shaft b¹⁵ are fixed a series of eccentric cams 85 b¹⁶ for clamping the strands of the fence against the base-plate b¹³ during the time the feed movement takes place. The rock-shaft b¹⁵ is reinforced by a brace yoke or bar b¹⁷, 90 fixed to the upper ends of said standards b¹⁴ directly over the shaft and provided at suitable intervals with downwardly-projecting portions b¹⁸, which bear on the shaft b¹⁵ between the eccentrics b¹⁶, thereby preventing 95 the springing of the shaft when the clamping action takes place. The outer ends of the base-plate b¹³ are provided with tenons b¹⁹, 100 which work in guideways b²⁰, shown as formed by the coöperation of the top rails of the machine-frame and angular guide-bars b²¹, fixed to said rails, as best shown in Figs. 27 and 29. The rock-shaft b¹⁵ is provided at its opposite ends with crank-arms b²², pivotally connected 105 to the upper ends of levers b²³, which are pivoted to the base-plate b¹³, as best shown in Figs. 27 and 29, and are connected by pitmen b²⁴ to wrist-pins b²⁵, adjustably securable for any desired throw in radial slots b²⁶ 110 of gear-wheels 16, carried by a counter-shaft 12, 115 17, which may be conveniently called the "feed-shaft" of the machine. This feed-shaft 17, as well as all the other moving parts of the machine, receives its motion indirectly 120 from the constantly-running main shaft 12, 125 to which the power is applied from any suitable source by a belt (not shown) which engages with a pulley 11 on the rear end of the shaft 12, as shown in Figs. 39 and 40. The main driving-shaft 12 is provided with a pair 130 of spur-gears 13, which engage with corresponding spur-gears 14 on intermediate studs 15, as best shown in the diagram view Fig. 40. The spur-gears 14 of the interme-

diate shafts 15 engage with the large spur-wheels 16 on the counter-shaft 17. These wheels 16 carry the wrist-pins b^{25} , which are connected to pitmen b^{24} for operating the 5 rock-shaft of the fence-clamp, as hitherto noted, and as best shown in Figs. 29 and 40. The feed-shaft 17 is therefore in constant motion. At each rotation of the gear-wheels 16 which operate the pitmen b^{24} the fence-clamp is given a complete reciprocation lengthwise of the machine in its guideways 10 b^{20} . If we assume the normal position of the clamp to be as shown in Figs. 3, 27, and 29, the feed actions may be readily understood. 15 Under the continued movement of the pitman-driving gear-wheels 16 the first thing done will be to operate the rock-shaft b^{15} , thereby throwing the eccentric cams b^{16} downward for coöperation with the base-plate b^{13} 20 to clamp the fence. Then under the continued movement of the wheel 16 the clamp will be carried rearward, taking the fence therewith to the rearmost limit of the clamp's travel or until the wrist-pins pass the center, and as quick as the pitmen begin to move in the opposite direction the rock-shaft will be turned upward, thereby freeing the eccentric b^{16} from the fence and the base-plate b^{13} , thus releasing the fence. Under 25 the continued movement of the wheel 16 the clamp will be restored or returned over the fence to its normal position, as shown in Fig. 3. Under the rearward movement of the clamp and the chains b^{11} , to which the clamp 30 is attached, the delivery-rollers were operated by the said chains through the pawl-and-ratchet drives to move the same forward for taking up the slack and coöoperating in the feed movement of the fence. Then on 35 the release of the clamp and the return of the clamp and chains the loose sprockets b^8 will turn backward, while the retaining ratchet-and-pawl devices b^6 b^7 will remain where set and hold the fence taut, as hitherto 40 noted. During this time that the fence-clamp makes its forward and return motion the loop-wires 1 and 2 are properly disposed with respect to the filling and lock wires, the twists are made, and the twisters are released from the fence under the action of the 45 parts which will now be described. It will be convenient, however, to first note a pair of constantly-running counter-shafts which receive motion from the primary driving-shaft. At its forward end the said main shaft 12 is provided with a sprocket-wheel 18, connected by chain 19 with a small sprocket 20 on a counter-shaft 21, located at the center of the machine at a dip in the 50 frame, as best shown in Fig. 4. This shaft 21 runs constantly and, through mechanism which will later be described, intermittently operates the master-wheel member in the drive for the twisters. On the said primary driving-shaft 12 is also fixed a sprocket 22, connected by a chain 23 (best shown in Figs. 3 and 40) to a sprocket 24 on a counter-shaft

25, located on the forward-projecting angle of the machine-frame. From the shaft 25, which is in constant motion, the traveling 70 carriers, which properly dispose the loop-wires, receive an intermittent motion through a suitable drive, which will be described under the next heading.

The loop-forming mechanism.—The loop-wires 1 and 2 pass directly from their unwinding-spools to the guide-sheaves c of a pair of traveling carriers c' and c^2 . The sheaves c are in pairs at the rear end of each carrier, and the loop-wires pass between the 80 said sheaves. Of the two traveling carriers c' and c^2 the member c' is fixed to the upper running section of an endless chain or belt c^3 and the other member c^2 is fixed to the under running section of said chain or belt 85 c^3 . The upper carrier c' is mounted for sliding movement on a parallel pair of guide-rods c^4 c^5 , spaced apart from each other and extending crosswise of the machine, and the lower carrier c^2 is similarly mounted on another similar pair of guide-rods c^6 c^7 , located directly below the guide-rods c^4 and c^5 . A true guiding action is thus secured for the traveling carriers c' and c^2 , with the same 90 mounted to move simultaneously in opposite 95 directions crosswise of the machine under the motion of the chain c^3 . The sprocket-chain c^3 is mounted on suitable sprockets c^8 , carried at the rear ends of short shafts c^9 , disposed lengthwise of the machine. One of 100 these shafts c^9 carries at the forward end thereof a beveled gear c^{10} , which can be made to engage with either member of a pair of clutch-faced beveled gears c^{11} , which are loose on a cross-shaft c^{12} , supported in a bearing-bracket c^2 rising from the main frame, as 105 best shown in Fig. 5. Between the clutch-faces of said gears c^{11} is mounted the shifting member c^{13} of the clutch, which is splined to the shaft and provided with double faces for 110 engaging with either of said gears when shifted to opposite extremes. The shaft c^{12} carries at its inner end a sprocket-wheel c^{14} , which is connected by a chain c^{15} to the sprocket c^{16} on the constantly-running counter-shaft 25, which is kept in constant motion. 115 A trip-rod c^{17} extends crosswise of the machine, as best shown in Fig. 5, and is provided with a pair of collars c^{18} , adjustable thereon and adapted to be secured thereto in any desired position by set-screws c^{19} . The lower member of the two traveling carriers—to wit, the member c^2 —is provided with a perforated arm c^{20} , which works on said trip-rod c^{17} between the collar c^{18} . The trip-rod c^{17} at one 120 end is pivotally connected to the crank-arm of a rock-shaft c^{21} , as best shown in Fig. 6. The rock-shaft c^{21} has fixed thereto the shipper-fork c^{22} , which acts on the shifting clutch member c^{13} . A counterweighted lever c^{23} is 125 loosely pivoted on the rock-shaft c^{21} and is provided with a lug c^{24} , which works between a pair of jaws c^{25} , radially projecting from the hub of the shipper-fork c^{22} , as best shown in

Figs. 5, 6, and 7. The weighted lever c^{28} has feet c^{26} of such length in respect to its pivotal center that one foot will rest on a trip plate or table c^{27} when the lever is in the position shown in full lines in Fig. 5. When this trip-table c^{27} is pulled out from under the weighted lever, the said lever will drop under the action of gravity into the position shown in dotted lines in Fig. 5, and thereby throw the shifting member c^{13} of the clutch into engagement with the outer member of the pair of double gears c^{11} . If the pivoted lever has stood on the other foot, the weighted lever would fall in the opposite direction and throw the clutch member into engagement with the inner member of said beveled gear c^{11} , and thereby driving the shaft c^{12} in the opposite direction. At the opposite limits of the travel of the carriers c' and c^2 the arm c^{20} of the lower carrier c^2 will strike one or the other of the collars c^{18} on the trip-rod c^{17} , and thereby shift the clutch into its open or central position and bring the weighted lever into an inclined position on one side of the vertical line, so as to be in position to become operative to shift the clutch into engaging position when the table c^{27} is drawn out from under the foot of the weighted lever c^{28} . The table c^{27} is under tension or strain to assume its normal position under the feet of the weighted lever. As shown, it is under tension from a spring $c^{27\frac{1}{2}}$, but at the proper time may be pulled out against the tension of said spring through connections which will be now noted. As shown best in Fig. 8, the said trip-table c^{27} is provided with a stem c^{28} , which extends through fixed parts of the framework, spaced apart from each other, one of which serves as a base of reaction for the spring $c^{27\frac{1}{2}}$, encircling the stem, and is marked c^{29} . The rear end of the stem c^{28} is notched or of hook shape and is engaged by the forward end of a hook-rod c^{30} , which extends to a rocker c^{31} . The rocker c^{31} is fixed to a rock-shaft c^{32} , journaled in the framework of the machine near the center of the same, directly below the twisting mechanism, and the said rock-shaft c^{32} is provided with a crank-arm c^{33} , which is connected by a rod c^{34} to the upper end of a pivoted cam-lever c^{35} . (Best shown in Fig. 15.) This cam-lever c^{35} is provided with a roller-stud c^{36} , which engages in a cam-channel c^{37} , formed on the profile face of a cam c^{38} , which is fixed to the feed-shaft 17, as best shown in Figs. 3 and 40. By these connections a positive rocking motion is imparted to the shaft c^{32} at the proper time. The hook-ended rod c^{30} , which engages with the hook end of the trip-table stem c^{28} , rides over a cam-lug c^{39} on the bracket c^{29} and is subject to a spring c^{40} , tending to hold the same down against the said cam-lug. By the action of this cam-lug c^{39} the hook-ended rod c^{30} is disengaged from the table-stem at the proper time, thereby permitting the spring $c^{27\frac{1}{2}}$ to instantaneously restore the said trip-table to its normal position under the feet of the weighted lever c^{28} . Through the driving connections

above noted it is obvious that the traveling carriers c' and c^2 will receive an intermittent reversely-reciprocating motion at the proper time and that they will come to a stop and remain stationary for a proper interval at the opposite limits of their travel. This interval of rest permitted to the traveling carriers c' and c^2 at the opposite limits of their travel is sufficient to afford time for the twisters to act and the fence to be moved forward one step under its intermittent feed hereinbefore described.

As the loop-wires are carried across the machine under the action of the traveling carriers c' and c^2 they are stretched around suitable corner-studs f , which, as shown, are in the form of rollers carried on the upper ends of plungers f' , as best shown in Figs. 3 and 28 to 30. The plungers f' are mounted in suitable guide-keepers f^2 , which are formed integral with rocker-plates f^3 , pivoted to the frame of the machine, as shown at f^4 in Fig. 29. The crank-arms of these rocker-plates f^3 have attached thereto depending screw-ended draw-bolts f^5 , which work through swivels f^6 , and are provided with springs f^7 , which react between said swivels f^6 and thumb-nuts f^8 , working on the ends of the draw-bolts and serving as a means to adjust the tension of said springs. In virtue of this mounting of said corner-studs f they will yield inward toward the center of the fence at the time when the drawing action thereon takes place under the action of the twisters on the loop-wires to form the stays of the fence, as shown by the dotted lines in Fig. 28. When that drawing action occurs, the rockers f^3 will turn on their pivots f^4 against the tension of the springs f^7 . This yielding action is essential, or otherwise something would have to break. The plungers f' , which carry the corner-studs f , are connected by rods f^9 to crank-arms f^{10} on a rock-shaft f^{11} , extending crosswise of the machine. The shaft f^{11} is provided with another crank-arm f^{12} , having connected thereto a cam-actuated rod f^{13} for imparting a positive up-and-down motion to the said corner-studs f at the proper times. As shown, the rod f^{13} is provided at its rear end with an elongated slot f^{14} , through which passes the feed-shaft 17. On the shaft 17 is fixed a cam-wheel f^{15} , having a profile cam-channel f^{16} , which is engaged by a stud-roller f^{17} on the cam-rod f^{18} . Under the action of this cam-wheel f^{16} and the connections therefrom the said corner-studs f will be withdrawn downward at the proper time to release the fence after the twists have been made and permit the forward feed motion of the fence. Instantly after the fence begins to move forward the corner-studs f will again be thrown upward, so as to be in position to engage the loop-wires when the traveling carriers c' and c^2 are started into action. In this connection it should be noted that the traveling carriers c' and c^2 pass outward beyond the corner-studs and so remain in that stationary

position until the fence is started forward by the feed mechanism. Hence under the feed movement on the fence the loop-wires will be pulled forward outside the corner-studs. It follows that when the carriers move across the machine the studs will intercept the wires at the proper points to form the corners for the loops, as hitherto noted and as shown in Figs. 2, 3, and 28 of the drawings. The carriers start immediately after the fence begins its feed-step.

The twisting mechanism.—The stay-twisters comprise small gear-wheels h and removable cores h' , which are secured to the wheels h for rotary movement therewith by keys h^2 , as best shown in Figs. 31 and 32. The wheels h and the cores h' are radially slotted to afford registering mouths h^4 for engaging with the wires. Moreover, all of the twisters have cores with the exception of the central twister and are constructed to be expansible and contractible. To this end the cores of said expansible twisters are free for a sliding movement lengthwise of the wheels h and are normally held in their innermost position or with their faces in line with the faces of the wheels under spring tension. As shown, the ends of the cores h' facing the central or base member are engaged by slotted washers h^5 , having attached thereto draw-rods h^6 , extending through said ends of the cores into open-ended recesses e and provided with spiral springs h^7 , reacting between the nuts of the draw-rods and the base ends of said recesses. The springs h^7 will thus hold the cores in their normal position, as shown in Fig. 30, until the draw begins and then permit the cores to yield in the direction of the draw, as required, as shown in Fig. 33. This action is obvious from an inspection of Figs. 30 to 33, inclusive. All of the twisters which operate on the loop-wires to form the vertical stays of the fence are mounted in holders h^8 , which are keyed fast to a rock-shaft h^9 , extending crosswise of the machine. The holders h^8 have cap-sections h^{10} , which are removably fitted to the outer end portions of the holders proper and when in position serve to hold the twisters in proper working position on the holders, as may be readily understood from an inspection of Figs. 9 to 11, inclusive. The holders proper, h^8 , and the cap-sections h^{10} are provided with jaws h^{11} , spaced apart to afford flaring or bell-shaped mouths h^{12} for registration with the mouths h^4 of the twisters to engage and release the wires. A pair of shafts h^{13} h^{14} extend through all the holders h^8 , which act on the loop-wires to form the vertical stays. These two shafts h^{13} and h^{14} are provided with spur-gears h^{15} , as shown in Fig. 3, which mesh with each other and cause the said shafts to turn in opposite directions. Each of these shafts is provided with half as many intermediate gears h^{16} as there are twisters to be operated. The intermediate gears h^{16} on each of said shafts engage with alternate members of the twisters.

Hence the adjacent twisters turn in opposite directions, as required, to give the reverse twists to the stays between successive spaces. Moreover, the intermediate gears h^{16} and the co-operating twisters are so proportioned in size or number of teeth as to secure differential movements to the different twisters, as shown in the diagram views, Figs. 75 to 24. This is to impart a greater number of twists to the loop-wires in the wider spaces as compared with the narrower spaces. On this particular machine, as may be seen by reference to said diagram views, Figs. 19 to 24, provision is made for three differentials in the number of twists. On the said rock-shaft h^9 are loosely mounted a pair of wheels side by side, which have the relation of master and mate. The master-wheel is marked h^{17} and its mate h^{18} . The positions and relations of these wheels to each other and the other parts are best shown in Figs. 8 and 9 and 15 to 17. The mate wheel is constantly in mesh with a pinion $h^{19\frac{1}{2}}$ on the shaft h^{13} . The master-wheel h^{17} is normally in engagement with a pinion h^{19} on the constantly-running counter-shaft 21. The master-wheel is a spur-gear and is provided with a pivoted section h^{21} . This section h^{21} is subject to the action of the spring h^{22} , tending to throw said section into its outermost position for completing the spur-gear and maintaining connection with the pinion h^{19} . The pivoted section h^{21} is provided on its profile face with a stud-roller $h^{21\frac{1}{2}}$, which at the proper time in the revolution of the master-wheel will contact with the pivoted member or jaw h^{23} of a two-fingered or two-jawed trip h^{20} , which is mounted as a collar on the shaft 21. Between the pivoted jaw h^{23} and the fixed jaw h^{24} of said trip h^{20} is placed a spring h^{25} , tending to separate the fingers. The whole trip h^{20} is free to turn on the shaft 21. When the stud-roller $h^{21\frac{1}{2}}$ first strikes the upper end of the pivoted finger h^{23} , the trip h^{20} will be rocked on the shaft 21, and simultaneously therewith will yield against the spring h^{25} until the finger h^{23} finds a bearing on the hub of the trip h^{20} . In the meantime the stud-roller $h^{21\frac{1}{2}}$ will ride up the finger h^{23} , and thereby the pivoted section h^{21} of the master-wheel will be thrown radially inward or from the position shown in Figs. 8 and 16 into the positions shown in Figs. 15 and 17. By this action the master-wheel will be thrown out of connection with the pinion h^{19} , and certain other results will follow under the control of that pivoted section h^{21} in virtue of certain details, which will now be named. The free end of said pivoted section h^{21} of the master-wheel has two lateral projections h^{29} and h^{30} , and when the said section is in its outermost position, as shown in Figs. 8 and 16, the lateral projection h^{29} will engage with the profile shoulder h^{31} on the mate wheel h^{18} , thereby interlocking or coupling together the said master and mate wheels for common movement, as best shown in Figs. 8 and 16. When, however,

the said pivoted section h^{21} is forced inward by the trip h^{20} into the position shown in Figs. 15 and 17, the lateral projection h^{29} will come into a position to clear the profile shoulder h^{31} of the mate wheel and the other lateral projections h^{30} will come into position to engage a fixed lug h^{32} , projecting from a part of the main frame, as shown in Fig. 17, thereby locking the master-wheel to the frame and holding the same in a fixed position, while the mate is free for a reverse motion to permit the natural reaction or limited unwinding of the twist. This reverse motion is produced by means which will now be noted. The mate wheel has a ratchet h^{33} on one of its profile faces. On the rock-shaft h^9 is mounted a pawl-carrying lever h^{34} . (Shown detached in Fig. 12.) This pawl-lever h^{34} is clamped to the shaft h^9 under sufficient friction to remain where set, but is sufficiently light to permit the same to move on the shaft when required. To the upper end of the lever h^{34} is pivoted a pawl h^{35} , notched on its head to afford a pair of jaws h^{36} . The heel of the pawl overreaches a laterally-projecting stop-lug h^{37} , as best shown in Figs. 9 and 12, to prevent the pawl from falling unduly far backward. On the rock-shaft h^9 , adjacent to the lever h^{34} , is loosely mounted a rocker-arm h^{38} . (Shown detached in Fig. 14.) This rocker-arm h^{38} is provided with a lateral stud h^{39} , which plays between the jaws h^{36} of the pawl h^{35} , as best shown in Fig. 9. Hence by pulling downward on the rocker-arm h^{38} by means of the arm c^{41} on the shaft c^{32} and the connecting-link c^{42} the pawl h^{35} may be made to engage with the teeth of the ratchet h^{33} on the mate wheel h^{18} , and thereby to turn the mate wheel backward on the rock-shaft h^9 , while the master-wheel h^{17} stands still. This is done during the initial downward movement of said rocker-arm h^{38} and occurs directly after the trip is effected and the master-wheel is brought to a dead-stop. Then under the continued downward movement of the rocker-arm h^{38} the same will come in contact with a crank-arm h^{40} , (shown detached in Fig. 13,) which is keyed to the rock-shaft h^9 alongside of the rocker h^{38} and provided with a laterally-projecting end fitted with a set-screw h^{41} , which affords a means for adjusting the point of contact between said crank-arm and said rocker. As quick as the rocker h^{38} comes in contact with the crank-arm h^{40} , fixed to the rock-shaft, the shaft itself and all the holders h^8 , together with the train of gears carried thereby, will rock together, and thereby shift the parts from the position shown in Fig. 8 to the position shown in Fig. 15. By the return movement of the mate wheel h^{18} on the rock-shaft h^9 , as above described, all the twisters will through the trains of gears operated by the mate wheel be returned to normal position in respect to the jaws of the holders, thereby bringing the mouths of the twisters into registration with the mouths of the holders for releasing the wires. Hence when the rocker-

arm h^{38} begins to act on the crank-arm h^{40} , and thereby to rock all the holders h^8 , the twisters and the holders will readily free themselves from the wires and the mouths of the twisters and the holder will remain in proper registration ready for reengagement with the next set of loop-wires on the return to the position shown in Fig. 8 after the fence has been thrown forward one step, which occurs, of course, while the holders are in their released position. The side twisters are also on the same rock-shaft h^9 and are operated simultaneously with the stay-twisters, as above described, but differ from the stay holders and twisters in certain details only, which will be presently noted.

In the twisting action the mouths of all the twisters are rotated past the mouths of the holders. They will pass by different distances according to their respective differentials in gearing. When the unwinding occurs, to permit the natural reaction of the twists all of the twisters will be rotated back to the proper positions for causing the mouths h^4 thereof to register with the mouths h^{12} of the holders. This is necessary, of course, to give the free release from the twisted wires when the holders are rocked upward. Under the rocking motion of the holders h^8 with the shaft h^9 , as above described, the entire train of gears carried by the holders will remain in the position at which they stood when the release occurred, or, otherwise stated, in the position which they stood when the loose rocker h^{38} came into contact with the set-screw h^{41} of the fixed crank-arm h^{40} . The entire train being carried by the holders h^8 , the respective members thereof will not move in relation to each other under the rocking motion of the shaft h^9 and holders h^8 , and hence when the holders and twisters are again lowered at the proper times to grab the next set of loop-wires the mouths h^4 of the twisters will be in registration with the mouths h^{12} of the holders. The master-wheel h^{17} remains locked to the frame or in its stationary position until the holders have again been thrown down and the next set of loop-wires have been grasped by the twisters, at which time the trip h^{20} will be rocked backward on the shaft h^{21} , so as to bring its finger h^{23} out from under the stud-roller h^{22} , thereby permitting the pivoted section h^{21} of the master-wheel to be thrown outward by its spring h^{22} , reestablishing the working relation of the master-wheel to the pinion h^{19} and coupling the mate to the master-wheel, as shown in Figs. 8 and 15. To effect this release of the trip h^{20} , the said trip is provided with a depending arm h^{42} , which plays between a pair of stop-pins h^{43} , projecting from the frame, as indicated in Fig. 15, and this trip-arm h^{42} is provided with a lateral stud h^{44} , adapted to be engaged by the hook end of a counterweighted lever h^{45} . The counterweighted lever h^{45} is carried by the lower arm of the lever c^{31} , keyed to the rock-shaft c^{32} , which was hitherto noted.

in connection with the trip-table pull-rod c^3 when describing the trip mechanism for the traveling carriers c' and c^2 . The hook end of the counterweighted lever h^{45} is cam-shaped and adapted to strike a fixed pin h^{46} (shown in Figs. 8 and 15) for disengaging the lever h^{45} from the stud h^{44} of the trip-arm h^{42} when the trip h^{20} has been moved sufficiently far backward to pull the finger h^{23} out from under the stud-roller h^{22} . The recess of the hook is cam-shaped at its back to permit the stud h^{44} to rise out of said recess when the collar is rocked forward under the contact of the stud-roller $h^{21\frac{1}{2}}$ with the trip-finger h^{23} . The rocking motion on the shaft c^{32} , as imparted thereto from the rod c^{34} and the other connections to the cam c^{38} on the feed-shaft 17 hitherto described, comes at the right time to effect this releasing action of the trip h^{20} .

Having regard to the side twisters above noted as carried by the rock-shaft h^9 and operated simultaneously with the stay-twisters, the constructions and relations thereof to the shaft h^9 and to the lock-wires 4 and horizontal sections of the loop-wires 1 and 2, upon which said side twisters act, may be readily understood from an inspection of Figs. 3, 25, 26, 28, and 29. The said side twisters are marked k and are in the form of beveled gears slotted to afford the mouths h^4 for engagement with the wires and are provided with stems k' , which fit into suitable bearing-seats h^2 , provided in the ends of the holders k^3 , as best shown in Figs. 25 and 26. When the parts are in working relation, the beveled gear-faces of the twisters k engage with corresponding beveled gears k^4 , carried on lateral stud-shafts k^7 , projecting from the faces of the holders k^3 . The beveled gears k^4 have formed on the same hub gears k^5 , which are operated from the proper members of the intermediate gears h^{16} , carried by the lower member h^{18} of the pair of shafts h^{13} and h^{14} , which extend through the stay-holders h^8 . The holders k^3 for the side twisters have jaws k^6 , extending lengthwise of the holders for affording the mouths h^{12} to coöperate with the mouths h^4 of the twisters above noted. The side twisters and their action may be regarded as having been described in the description of the stay-twister mechanism. The side twisters are removed from the parts shown in Figs. 8 and 15.

All the parts of the machine have now been specified with the exception of the winding-up reel and the parts which coöperate therewith to dispose of the fence after it has passed through the delivery-rollers b^3 b^4 . This reel and its immediately coöoperating parts for disposing of the fence may, for distinction, be called the "fence-shedding mechanism."

The shedding mechanism.—The winding-up reel (best shown in Figs. 4 and 34 to 37) is a collapsible reel and is made up of a pair of heads p p' and a series of trundles or staves p^2 p^3 . The reel-head p' is fixed to a short

shaft p^4 , free for rotary motion only. The other head p is fixed to the inner end of a short shaft p^5 , which is free for both a rotary and a sliding motion. The outer end of the shaft p^5 is taken hold of by a swivel p^8 , carried by a hand-lever p^9 for sliding the said shaft p^5 and the reel-head p whenever so desired. The reel-heads p and p' are provided on their inner hubs with seats p^{10} and p^{11} for receiving the staves or trundles p^2 p^3 . Of the said seats p^{10} and p^{11} the seats p^{10} are of dovetailed shape, while the seats p^{11} are rectangular. The particular stave p^2 is also dovetailed at its ends for coöperation with the dovetailed seats p^{10} in the hubs of the reel-heads. This dovetailed stave p^2 is first entered into the seats p^{10} , and the wires 3 and 4 are made fast thereto by engaging the same over buttons or studs p^7 thereon. The other staves p^3 are then placed in position within the seats p^{11} by a radial movement, and as the reel is wound the wires passing thereover will hold the same in working position. In virtue of this construction it is obvious that when the fence-coil reaches its limit of size on the reel it may be readily removed therefrom by simply operating the hand-lever p^9 . The outward movement of that lever p^9 will withdraw the movable reel-head p from the reel-staves p^2 and p^3 , allowing the latter to collapse and be readily removed from the interior of the coil. The staves are then replaced and the fence 4 reattached, and all is ready for the next coil. The reel-shafts p^4 and p^5 are both provided with a large spur-wheel p^6 , fixed against sliding motion. These spur-gears p^6 engage with small spur-gears p^{12} , carried on the outer ends of the friction-clutch members p^{13} , which are loosely mounted on a constantly-running counter-shaft p^{15} for coöperation with the sliding clutch members p^{14} , carried by said shaft. The shaft p^{15} receives motion from the primary driving-shaft 12 through a chain p^{16} , running over sprockets p^{17} and p^{18} , located, respectively, the former on the primary shaft 12 and the latter on the clutch-shaft p^{15} . The sliding clutch members p^{14} are subject to the action of bell-crank shipper-forks p^{19} . (Best shown in Fig. 34.) These shipper-forks p^{19} are pivoted at their elbows to suitable bearing-brackets a^3 , projecting inward from the machine-frame. The long arms of the shipper-forks p^{19} are pivotally connected together and to a common link p^{20} , which depends from the central arm of a counterweighted bail p^{21} , which is pivoted to the shaft of the lower member b^4 of the delivery-roller. The bail p^{21} is also provided with a pair of arms p^{22} at its opposite ends, in which is journaled a tension or tightening roller p^{23} , to which the fence is subject as it leaves the delivery-rollers and passes to the winding-up reel. Under the action of the mechanism above described the winding-up reel is automatically driven with an intermittent action, as required to wind up the fence, at each feed movement. Otherwise

stated, the reel coöperates with the feed mechanism for the fence described in the early part of the specification. Normally and at all times while the fence is being held stationary the take-up roller p^{28} will act on the wires of the fence between the delivery-rollers and the winding-up reel and reinforce the clamping action of the delivery-rollers b^8 and b^4 to hold the fence taut. When, however, 5 the fence is fed forward by the fence-clamp and the delivery-rollers b^8 b^4 , as hitherto described under the heading "Feed mechanism," the slack in the fence between the delivery-rollers and the reel thereby produced 10 will permit the counterweighted bail p^{21} to drop, thereby throwing the long arms of the bell-crank shipper-forks p^{19} downward and causing the short arms thereof to shift the movable members p^{14} of the friction-clutches 15 20 into working engagement with the loose members p^{18} , which carry the constantly-running gears p^{12} . Hence the reel will thereby be immediately started into action and will continue to run until the fence is wound up sufficiently far to put on the coil the amount 25 moved forward under the feed movement imparted to the fence by the fence-clamp and delivery-rollers. As quick as that occurs the counterweighted bail p^{21} will be brought 30 35 back upward by the taut wires between the reel and the delivery-rollers, thus restoring the long arms of the bell-crank shipper-forks p^{19} into their uppermost position and opening the friction-clutches. This of course stops the reel. When the time comes for the removal of a coil of fence, the wires must of course be cut between the delivery-roller and the reel. The reel is then collapsed, the coil removed, the reel reassembled, the wires re- 40 45 attached, and all is again ready for action. In view of the special construction of the reel hereinbefore described it is obvious that the coils or sections of the fence may be quickly shed and all the parts brought back to working position. This is done without stopping the machine. As the fence is held taut by the delivery-rollers b^8 and b^4 , the separation can take place and the coil be removed without interfering with the action of the other 50 parts of the machine. This is an important advantage.

Operation: All the parts of the machine have now been specified, treating the same in groups, and the actions of the respective groups of mechanisms have been fully stated in connection with the detailed description of the parts. Hence it is thought that a brief statement of the general action with special reference to the timing of the different groups 55 60 of mechanisms relative to each other will be sufficient. The driving connections must be properly proportioned to permit the traveling carriers to dispose the loop-wires and come to stationary position at the opposite limits 65 of their travel during the time that the fence is being fed forward one step, or, otherwise stated, during a half-turn of the feed-shaft 17.

During the time that the fence is thus fed forward one step or a half-turn of the feed-shaft 17 the master and mate wheels h^{17} and h^{18} must stand idle and the holders h^8 and k^3 must remain in their released position, so as to afford clearance for the movement of the fence. It follows that all the actions required from the twisters must take place during the 75 return or idle movement of the fence-clamp. By proportioning the driving connections in such a way that one complete revolution can be given to the master and mate wheels h^{17} and h^{18} during one-eighth turn of the feed-shaft 17 all the different functions required from the twisting mechanisms may be secured and be distributed in respect to the feed-shaft in the following manner: Assume the feed on the fence as the starting-point. Then during the first four-eighths of the turn of the feed-shaft 17 the fence will be clamped and fed forward one step by the fence-clamp. Immediately after the fence starts to move the trip-table c^{27} is pulled out by the rod c^{30} from 80 under the weighted lever c^{28} , thereby starting the carriers c' and c^2 for disposing the loop-wires. The corner-posts f had been previously pulled down to permit the fence to start and were immediately returned to normal 85 position by the cam-wheel f^{16} and its connections, so as to coöperate with the carriers c' c^2 for disposing the loop-wires during the feed movement of the fence. Otherwise stated, before the feed-shaft 17 had completed its 90 first four-eighths turn the loops had been formed and the carriers c' and c^2 had reached 95 stationary positions at the opposite limits of their travel. During the fifth one-eighth part of the feed-shaft's revolution the fence-clamp is released from the fence and the twister-holders are lowered to their limit, thereby grabbing the wires, and coincidentally therewith the trip h^{20} is knocked out from under the roller $h^{21\frac{1}{2}}$ by the releasing-lever 100 h^{45} , thereby throwing the master-wheel into gear with the pinion h^{19} on the constantly-running counter-shaft 21. During the next or sixth one-eighth part of the feed-shaft's turn the said master and mate wheels h^{17} and h^{18} 105 110 make one complete revolution, thereby causing the twisters to make the twists in the wires, and when this revolution is completed the master-wheel is automatically tripped out of action and brought to a stationary position by 115 the coöperation of the stud-roller $h^{21\frac{1}{2}}$ and the trip-lever h^{28} , as described. Under the seventh one-eighth turn of the feed-shaft 17 the rocker h^{38} and the pawl-lever h^{34} are pulled down 120 from the full-line position shown in Fig. 8 into 125 the position shown in dotted lines in Fig. 15, thereby reversing the motion on the twisters for permitting the natural reaction of the twisters, and bringing all the twisters into such position that the mouths h^4 thereof will register with the mouths h^{12} of the holders. Then under the last or final one-eighth turn of the feed-shaft 17 the rocker h^{38} , acting on the fixed 130 crank-arm h^{40} , will rock the shaft h^9 , thereby

raising all the holders into the position shown in full lines in Fig. 15, thus releasing the fence and bringing all the parts into position to permit the feed on the fence, which was assumed as the starting-point. It should be noted that the rocker h^{38} and the pawl-carrying lever h^{34} are returned to their normal positions on the shaft h^9 by a positive motion from the cam c^{38} through the connections c^{32} to c^{42} , inclusive. The holders themselves would of course drop down by gravity as fast as permitted by the said cam and connections to said rocker h^{38} ; but the said rocker and the pawl-lever h^{34} require an additional 10 turn movement on the shaft h^9 itself in order to bring the same into normal position relative to the other parts on said shaft, as shown in Figs. 8 and 9.

During the time that the feed movement on the fence took place, as above described, the fence would be automatically wound up on the reel, as the latter would start into action by the accumulation of slack in the fence between the delivery-rollers and reel, all as 25 fully described under the heading "Shedding mechanism."

It will be understood, of course, that the machine herein disclosed is capable of many modifications without departing from the principle of the invention. It will also be understood that many of the features of the invention herein disclosed are capable of use on a hand-machine.

Respecting the twisting and untwisting action, perhaps attention should be directed to a certain detail as to the proportion of certain elements of the drive in order to secure the desired results. The mate wheel h^{18} has fifty-six teeth, and the pinion $h^{18\frac{1}{2}}$, engaged therefore, on the driven member h^{13} of the intermediate shafts h^{13} and h^{14} has twelve teeth; or, otherwise stated, these members of the twister-drive are related as one to four and one-half. Hence in the twisting action the one revolution of the mate wheel h^{18} will produce four and one-half turns of the intermediate shafts h^{13} and h^{14} , thereby turning the twistors forward past their centers or points, where their mouths h^4 would register with the mouths h^{12} of the holders. They will be turned different distances past said registering position, depending on the differentials in the respective drives therefor from said shafts h^{13} and h^{14} . When the mate wheel is reversed, it receives sufficient motion to turn the pinion $h^{18\frac{1}{2}}$ just one-half revolution backward. Hence the twistors are bound to come to registering position.

What we claim, and desire to secure by Letters Patent of the United States, is as follows:

1. In a wire-fence-making machine, the combination with means for holding the fence taut and moving the same forward with an intermittent action, of a pair of traveling carriers for the loop-wires, movable crosswise of the machine one above and the other below

the filling-wires, for disposing the loop-wires in proper position to embrace the filling-wires to form the vertical stays of the fence, when the loops are twisted together between the filling-wires, substantially as described.

2. In a wire-fence-making machine, the combination with means for holding the fence taut, and moving the same forward with an intermittent action, of a pair of traveling carriers for the loop-wires, movable crosswise of the machine, one above and the other below the filling-wires, and corner-studs around which said loop-wires are stretched by said traveling carriers to aline the loop-wires in proper position to embrace the filling-wires and receive the twisting action, substantially as described.

3. In a wire-fence-making machine, the combination with means for holding the fence taut and moving the same forward with an intermittent action, of a pair of traveling carriers for the loop-wires movable crosswise of the machine, one above and the other below the filling-wires, simultaneously, in opposite directions, and means for automatically reversing the direction of the travel of said carriers on reaching predetermined limits, substantially as and for the purposes set forth.

4. In a wire-fence-making machine, the combination with means for holding the fence taut and moving the same forward with an intermittent action, of a pair of traveling carriers movable crosswise of the machine, simultaneously, in opposite directions, one above and the other below the filling-wires, to properly dispose the loop-wires, and corner-studs around which the said loop-wires are stretched by said carriers, which corner-studs are movably mounted for assuming their wire-engaging and wire-releasing positions, substantially as described.

5. In a wire-fence-making machine, the combination with carriers for disposing the loop-wires to embrace the filling-wires, of twist-ers for twisting together said loop-wires between the filling-wires, and corner-studs around which the loop-wires are stretched by said carriers, which corner-studs are mounted for a yielding action under the draw from the stays in the twisting action, substantially as described.

6. In a wire-fence-making machine, the combination with means for holding the fence taut and moving the same forward with an intermittent action, of a pair of carriers for the loop-wires, and an endless chain or belt movable over suitable wheels crosswise of the machine above and below the filling-wires, with one of said carriers secured to the over-running section and the other to the under-running section of said chain or belt, substantially as and for the purposes set forth.

7. The combination with means for holding the fence taut, and moving the same forward with an intermittent action, of an endless chain or belt mounted, on suitable driving-

- wheels, to run crosswise of the machine, one section above and the other below the filling-wires, a pair of carriers for the loop-wires secured one to the upper and the other to the 5 lower section of said chain or belt, and a reversing drive for said chain or belt including an automatic trip operated by the carriers to reverse the motion of the belt or chain at the proper times, substantially as described.
- 10 8. In a wire-fence-making machine, the combination with means for properly disposing the wires to receive the twists, of a series of twisters operative simultaneously to produce the twists and interlock said wires, which 15 twisters are constructed and arranged to allow a limited reverse motion to permit the natural reaction or limited unwinding of the twists and afford a ready release of the twisters, substantially as described.
- 20 9. In a wire-fence-making machine, the combination with means for properly disposing the wires relative to each other for receiving the twists, of a series of twisters operative simultaneously on the loop-wires to form the 25 vertical stays of the fence, some of which twisters are constructed to yield lengthwise of the stays, under the twisting action, to compensate for the draw produced by the twists, substantially as described.
- 30 10. In a wire-fence-making machine, the combination with means for properly disposing the loop-wires to embrace the filling-wires, of a series of twisters operative simultaneously to twist together said loop-wires, between 35 said filling-wires, for forming the vertical stays of the fence, which twisters are constructed and arranged to cause the adjacent members to twist in opposite directions for alternating the twists between the successive filling-wires, substantially as described.
- 40 11. In a wire-fence-making machine, the combination with means for properly disposing the loop-wires to embrace the filling-wires, of a series of twisters for simultaneously twisting 45 together said loop-wires between said filling-wires, to form the vertical stays of the fence, and differential drives for said twisters for producing a greater number of twists in the stays between the filling-wires widely 50 spaced apart than those narrowly spaced apart, substantially as described.
- 55 12. In a wire-fence-making machine, the combination with the series of wire-twisters, of a corresponding series of holders for said twisters, mounted for common movements for engaging and releasing the wires, substantially as described.
- 60 13. In a wire-fence-making machine, the combination with a rock-shaft, of a series of twister-holders rigidly secured to said shaft and a corresponding series of twisters carried by said holders, whereby all the twisters may be engaged and disengaged with and from the wires, under the rocking motions of 65 said rock-shaft, substantially as described.
14. In a wire-fence-making machine, the combination with a rock-shaft, of a series of twister-holders rigidly secured thereto, a corresponding series of twisters carried by said holders, and drives for said twisters, the 70 members of which drives are carried by the said rock-shaft and said twister-holders, substantially as and for the purposes set forth.
15. The combination with a twister, of a drive for the same including a pair of wheels 75 loose on a common shaft having the relation of master and mate, and means for coupling the mate wheel to the master-wheel and uncoupling the same therefrom, and the mate wheel in mesh or in strain with the twister-wheel, whereby the master-wheel may turn in a constant direction and the mate wheel be permitted to reverse for permitting the natural reaction or limited unwinding movement of the twist, substantially as described. 85
16. The combination with a rock-shaft, of a series of twister-holders fixed thereto, a corresponding series of twisters carried by said holders, and a drive for said twisters including a pair of wheels on said rock-shaft having 90 the relation of master and mate, and provided with means for coupling and uncoupling the same together, and a train of gears having a member in mesh with said mate, and all carried by said holders, substantially as described, whereby the master-wheel may run in a constant direction and the mate with the other members of the twister-trains be permitted to reverse, as required to permit the natural reaction or limited unwinding of the 100 twists, as set forth.
17. An automatic drive for a wire-twister including a constantly-running shaft having a pinion fixed thereto, a pair of wheels loose on a common shaft, which pair of wheels have 105 the relation of master and mate, with the mate forming one member of the train operating the twisters, means for coupling and uncoupling the master and mate, an automatic trip for connecting and disconnecting 110 the master-wheel with said constantly-running pinion, and means controlled by said trip to effect the coupling and uncoupling of said master and mate wheels, substantially as described. 115
18. The combination with the rock-shaft having the series of twister-holders fixed thereto, of the series of twisters carried by said holders, a constantly-running shaft having a pinion, a pair of wheels loose on said 120 rock-shaft having the relation of master and mate, an automatic trip for connecting and disconnecting the master-wheel with said pinion on the constantly-running shaft, means controlled by said trip for coupling 125 and uncoupling the mate from the master wheel, a train of gearing connecting the mate with the twister wheels, all carried by said holders, and means for rocking said shaft and mate when the master-wheel is held stationary, substantially as and for the purposes set forth. 130

19. In a fence-making machine, the combination with means for holding the fence taut and moving the same forward with an intermittent action, of means for holding and supplying the filling and lock wires including three high sheaves between which the wires are passed for straightening the wires and holding the same under proper tension. 70
20. In a wire-fence-making machine, the combination with means for moving the fence forward under an intermittent action, of means for holding and supplying the filling and lock wires, including a pair of drums disposed to cause the wires to pass under one and over the other thereof, for equalizing the pull on the wire-holding spools and avoiding slack in the filling and lock wires of the fence, substantially as described. 75
21. In a wire-fence-making machine, the combination with means for intermittently feeding forward the fence, of means for holding and supplying the wires, including three high sheaves and a pair of drums to which the filling and lock wires are subject for straightening out the wires, putting a proper tension thereon, equalizing the pull from the spools and avoiding slack in those wires at the point where locked together into the fence, substantially as described. 80
22. In a wire-fence-making machine, a feeding-clamp for the fence having an intermittent reciprocating movement lengthwise of the machine, and comprising a resistance-plate over which the wires pass, and a rock-shaft above the wires having a series of eccentrics or cams for clamping the fence to the plate, substantially as described. 85
23. In a wire-fence-making machine, means for feeding and holding the fence taut, independent of the winding-up reel, comprising a pair of rollers between which the fence is passed at the delivery end of the machine, a pawl and ratchet in the drive for said rollers, the pawl-carrying member of which is loose on the driven-roller shaft and co-operates as one member of the supporting-wheels for a pair of sprocket chains or belts extending lengthwise of the machine, a clamp for the fence fixed to said chains, and means for imparting a reciprocating motion to said clamp, substantially as described. 90
24. In a fence-making machine, the combination with means for feeding the fence with an intermittent motion and for holding the same taut while the fence is being made, of shedding mechanism for disposing of the finished fence, comprising a collapsible winding-up reel for permitting the ready removal of the wound coil of fence. 95
25. In a fence-making machine, the combination with means for feeding the fence with an intermittent motion and for holding the same taut while the fence is being made, of shedding mechanism for disposing of the finished fence, comprising a winding-up reel and an intermittent feed for the same including an automatic controller operated by the fence itself, according as slack or taut between the delivery-rollers of the main machine and the winding-up reel. 100
26. In a fence-making machine, the combination with fence-forming mechanism and a winding-up reel, of intermediate fence-holding mechanism, whereby the coil of finished fence may be removed, at the reel, without stopping the other parts of the machine, substantially as described. 105
27. In a fence-making machine, the fence-feeding mechanism including the fence-clamp and the delivery-rollers co-operating therewith for holding the fence in whatever position it may be fed, whereby the fence, on the delivery side of the rollers, may be separated from the part within the machine, at will, substantially as described. 110
28. In a fence-making machine, the combination with the fence-feeding mechanism, including the fence-clamp and the delivery-rollers, substantially as described, of the winding-up reel and an intermittent drive for said reel including an automatic controller operated by the fence itself, according as slack or taut, between the delivery-rollers and the reel, substantially as and for the purposes set forth. 115
29. A wire-twister adapted to embrace the wires which are to be twisted together, and constructed to yield lengthwise of the twist to compensate for the shortening of the wires, substantially as described. 120
30. A wire-twister having a body portion adapted to embrace the wires which are to be twisted together and a core portion mounted to yield lengthwise of the body portion, whereby the twister is rendered expandable and contractible, substantially as and for the purposes set forth. 125
31. A twister-holder provided with body and cap portions co-operating to hold the twister in working position, substantially as described. 130
32. A twister-holder composed of body and cap portions which co-operate to hold the twisters in working position and having jaws which co-operate to afford mouths which register with the mouth of the twister, for grabbing and releasing the wires, substantially as described. 135
33. The combination with a twister, of a drive for the same, including a pair of wheels having the relation of master and mate, means for coupling and uncoupling the said two wheels together, and means for holding the master-wheel stationary while the mate wheel is turned backward to permit the natural reaction or limited unwinding of the twist, substantially as described. 140
34. In a wire-fence-making machine, a feed mechanism for the same, including a feeding-clamp adapted to engage and disengage the fence, and a crank-shaft having pitmen con- 130

nected to said clamp, for operating the clamp and moving the fence, substantially as described.

35. In a wire-fence-making machine, a feed mechanism for the fence, including the fence-clamp, the feed-shaft with crank disks and pitmen connected to said clamp, the delivery-rollers, the endless chains having the base-plate of the clamp connected thereto, and the pawl-and-ratchet devices for imparting motion to said delivery-rollers from said chains,

and holding the same wherever set, while permitting the chains to reverse their travel, substantially as described.

In testimony whereof we affix our signatures in presence of two witnesses.

MAURICE D. PENDERGAST.
JAMES M. WHIDDEN.
